UNITED STATES PATENT OFFICE.

MICHAEL L. PARKER, OF FREEPORT, ILLINOIS.

PLUMBER'S FURNACE.

Application filed February 25, 1924. Serial No. 695,108.

To all whom it may concern:

Be it known that I, MICHAEL L. PARKER, a citizen of the United States, residing at Freeport, in the county of Stephenson and State of Illinois, have invented new and useful Plumbers' Furnaces, of which the following is a specification.

This invention relates to new and useful improvements in a plumber's furnace, with special reference to economy in the construction, convenience in the handling, and safety in the operation thereof.

One of the specific objects of the invention is to provide means for catching fuel which may overflow from the priming pan, thus preventing it from flowing down the sides of the tank and possibly causing a disastrous fire. For this purpose, a depression is formed in the upper face of the tank, which also provides a seat for the spring which holds the priming pan and the shield or flue in operative position.

Another object is to provide an improved supporting means for the ladle and soldering iron, in combination with improved means for attaching and supporting the bail, which is a further insurance against accident.

A still further object of the invention is to provide improved means for supporting the priming pan and the shield or flue in such a manner as to insure sufficient air for combustion, yet effectually protecting the flame from wind or draft. Also the arrangement of the supporting means is such as to facilitate the disassembling of the various parts for cleaning or replacing them.

The essential principles of the invention and its advantages will be more fully explained in connection with the accompanying drawings, which illustrate the same in its preferred form.

In the drawings:

Figure 1 is a side view partly in elevation and partly in section showing the general assembly of the furnace.

Figure 2 is a plan view thereof.

Figure 3 is a front elevation of the invention.

Figure 4 is a detail view showing the manner of attaching the bail, and its relation to the furnace.

Figure 5 is a horizontal sectional view taken on the line 5-5 of Figure 3.

The device, of which my invention forms a part, includes a fuel tank 10 having in its

bottom a filler mouth 11, which is normally closed by a plug 12, and having also an air inlet mouth 13 to which is connected a nipple 14, adapted to be connected to a source of compressed air which is controlled by a valve 15. The tank 10 is also provided with a fuel outlet mouth 16, adapted to receive a fuel pipe 17 through which the passage of the fuel is controlled by means of a suitable valve 18. The fuel line includes a T 19 to which is connected a heating coil 20 located centrally above the tank 10, and terminating at its lower end in an elbow 21 to which is connected a burner tube 22, having a vent 23 through which the fuel is emitted.

A priming pan 24 is located beneath the coil 20 and fuel vent 23, and has a central depressed portion 25 for receiving the priming charge, the under surface of the portion 25 serving as a seat to receive the upper end of a conically wound coiled spring 26. The upper face of the tank 10 is provided with a central depression 27, which serves to catch any fuel which may overflow from the priming pan 24, so as to prevent the same from running down the sides of the tank and soiling the floor, or possibly resulting in a disastrous fire. The depression 27, of course, is of greater diameter than the priming pan 24, and serves also as a seat for the lower end of the coiled spring 26. This spring serves normally to hold the priming pan up against the burner tube 22, but may be easily compressed when it is desired to remove the priming pan, and to disassemble the other parts of the furnace.

In its normal position, the priming pan 24 is yieldingly held by the spring 26 against the burner tube 22 and the cylindrical shield or flue 28, the lower end of which is held within the flange forming the periphery of the pan. The shield 28 has an elongated opening 29 at one side, which receives the burner tube 22, and also serves to admit sufficient air for the complete combustion of the fuel, while the remaining portion of the shield is imperforate and effectually protects the flame against wind or draft.

The ladle holder 30 is provided with a plurality of laterally extending ears 31, which are perforated to receive the upper ends of posts 32, and are secured thereto by means of lock nuts 33. The lower ends of the posts 32 are threaded into suitable

bosses 34, extending upwardly from the tank 10. The ladle holder 30 is open at its bottom, where it is provided with a circular integral flange 35 extending downwardly, 5 and constituting a top rim for receiving and retaining the upper end of the shield 28. The ladle holder 30 provides a support for the soldering iron, and its lower portion is provided with inwardly projecting lugs 36 10 adapted to support the ladle. The upper end of the shield 28 is provided with notches 37, adapted to receive the lower edges of the lugs 36.

The upper portion of the ladle holder 30 15 is provided with two diametrically opposite ears 38, which are located in rear of two of the ears 31, and are adapted to receive the looped ends 39 of a bail 40. The sides of the bail, adjacent the looped ends 39, are 20 offset inwardly, as shown at 41, so that the bail when lowered to one side may rest on the upper ends of the adjacent posts 32, as shown in Figures 2 and 4. The bail when in this position extends nearly in a horizontal 25 plane, and may be used as a support for the handle of the soldering iron. When the bail is swung over to the opposite side of the furnace, it will drop downwardly out of the way.

30 In the operation of my improved furnace a small amount of liquid fuel is first allowed to flow into the depressed portion 25 of the priming pan, and is there ignited. The coil 20 quickly becomes heated, and therefore 35 after the vaporized fuel is ignited as it leaves the vent 23, as will be understood by those familiar with the art. In case the fuel overflows from the priming pan 24, it will collect in the depression 27 in the top 40 of the tank 10, so that there is no chance of its running down the sides of the tank and saturating the surrounding objects. The depression 27 also forms the seat for the spring 26, which holds the cup 24 and the 45 shield 28 in operative position. By compressing the spring 26, however, the cup may be readily lowered and removed as well as the shield 28, whereupon the other parts of the furnace may be easily taken apart. 50 The shield 28 is formed with an opening 29 in one side only, which is a great advantage when the device is used where there is considerable wind or draft. The location of the 55 filler opening in the bottom is a further insurance against fire since it is impossible to fill the tank without extinguishing the flame. The ladle holder 30 and the upper rim 35 of the shield are made in one integral piece and the bail is connected near the upper 60 edge of the ladle holder, so that the furnace may be easily carried with a ladle full of molten metal without any danger of its tipping over. The manner of connecting the 65 bail is also of great advantage, since the bail may be used to support the handle of

the soldering iron when the latter is being heated.

While I have shown and described in considerable detail the specific features of the invention, it is to be understood that these are merely illustrative, and that many modifications may be made in the various details of construction, size, and relative location of the various parts without departing from the salient features of the invention, or sacrificing the advantages thereof. 75

What is claimed is:

1. In a plumber's furnace, the combination of a fuel tank, a ladle holder supported above the tank, a priming pan and shield, 80 and yieldable means for supporting said pan and shield beneath the ladle holder with the shield in contact therewith, the upper surface of said tank having a depression underneath the priming pan for catching any overflow therefrom, said depression 85 forming a seat in which said yieldable means is supported.

2. In a plumber's furnace, the combination of a fuel tank, a ladle holder supported above the tank and having means for supporting a ladle, a burner beneath the ladle holder, a shield for the burner, and means for yieldably holding the shield in contact 90 with the ladle holder.

3. In a plumber's furnace, the combination of a fuel tank, a ladle holder supported above the tank and having means for supporting a ladle, a burner beneath the ladle holder, a shield for the burner having an 100 air opening on one side only, a circular flange integral with and depending from the ladle holder and normally receiving the upper end of the shield, a priming pan normally receiving and supporting the lower 105 end of the shield, and means for yieldably holding the pan and shield in their normal positions.

4. In a plumber's furnace, the combination of a fuel tank, posts extending upwardly therefrom, a ladle holder supported by the posts, means for supporting a ladle within the ladle holder, a pair of diametrically opposite ears extending from the ladle holder in rear of two of the posts, and a bail 110 pivotally connected to said ears and having inwardly offset portions adapted, when the bail is lowered to one side, to rest on the upper ends of said two posts, whereby the bail becomes a support for the handle of a soldering iron resting in said ladle holder. 115

5. In a plumber's furnace, the combination of a fuel tank, a ladle holder supported above the tank, a priming pan and shield, 120 and yieldable means for supporting said pan and shield beneath the ladle holder with the shield in contact therewith.

6. In a plumber's furnace, the combination of a fuel tank, a ladle holder supported above the tank and having means for sup- 125

porting a ladle, a burner beneath the ladle holder, a shield for the burner, a priming pan supporting the lower end of the shield, and means for yieldably holding the shield in contact with the ladle holder.

7. In a plumber's furnace, the combination of a fuel tank, a ladle holder supported thereon, a burner beneath the ladle holder, a priming pan beneath the burner, a depression

formed in the top of the tank for catching over flow from said pan, and yieldable pan supporting means having a portion disposed within said depression.

In testimony that I claim the foregoing as my own, I have hereto affixed my signature.

MICHAEL L. PARKER.
